(57) **CLAIM**

The design for a toothbrush handle, as shown.

DESCRIPTION

FIG. 1 is a perspective view a toothbrush handle in accordance with the present invention;

FIG. 2 is a top plan view of the toothbrush handle shown in FIG. 1;

FIG. 3 is a bottom plan view of the toothbrush handle shown in FIG. 1;

FIG. 4 is a left side elevation view of the toothbrush handle shown in FIG. 1, the right side thereof being identical;

FIG. 5 is a front elevation view of the toothbrush handle shown in FIG. 1; and,

FIG. 6 is a rear elevation view of the toothbrush handle shown in FIG. 1.

The broken line showing of environmental structure in FIGS. 1, 2, 4 and 5 is for illustrative purposes only and forms no part of the claimed design.
